UNITED STATES PATENT OFFICE

104,423

DESIGN FOR A COFFEE MILL CASING

David A. Meeker, Troy, Ohio, assignor to The Hobart Manufacturing Company, Troy, Ohio, a corporation of Ohio

Application February 13, 1935, Serial No. 55,396

Term of patent 14 years

To all whom it may concern:

Be it known that I, David A. Meeker, a citizen of the United States of America, residing at Troy, in the county of Miami and State of Ohio, have invented a new, original, and ornamental Design for a Coffee Mill Casing, of which the following is a specification, reference being had to the accompanying drawing, forming a part thereof, and which discloses the preferred embodiment, illustrated as comprising generally rectangular side portions and correspondingly shaped top and bottom portions, and in which

Fig. 1 is a perspective view of a coffee mill casing showing my new design; and

Figs. 2 and 3 are, respectively, an end elevational and a side elevational view thereof on a smaller scale.

As shown particularly in Fig. 1, the shading represents contrasting colors.

I claim:

The ornamental design for a coffee mill casing, substantially as shown and described.

DAVID A. MEEKER.
